VEGETABLE CUTTER

Samuel J. Popeil, 2920 N. Commonwealth Ave.,
Chicago, Ill.

Filed June 13, 1960, Ser. No. 60,930

Term of patent 14 years

(Cl. D89—1)

FIG. 1 is a perspective of a vegetable cutter showing my new design;

FIG. 2 is a front elevational view thereof;

FIG. 3 is a reduced scale top plan view thereof;

FIG. 4 is a side elevational view with the pusher in down position;

FIG. 5 is an opposite side elevational view;

FIG. 6 is a perspective view with the pusher in retracted position; and

FIG. 7 is a rear elevational view.

The essential features of my design are shown in full lines.

I claim:

The ornamental design for a vegetable cutter, as shown and described.
